UNITED STATES PATENT OFFICE.

DAVID JAMES, OF COFFEYVILLE, KANSAS.

COIN-CONTROLLED OPERATING MECHANISM.

SPECIFICATION forming part of Letters Patent No. 764,056, dated July 5, 1904.

Application filed October 27, 1902. Serial No. 129,017. (No model.)

To all whom it may concern:

Be it known that I, DAVID JAMES, a citizen of the United States, residing at Coffeyville, in the county of Montgomery and State of 5 Kansas, have invented a new and useful Coin-Controlled Operating Mechanism, of which the following is a specification.

This invention relates to coin-controlled operating mechanism for vending-machines, 10 and has for its object to produce a simple operating device capable of use in connection with that type of vending-machine disclosed in my concurrent application, Serial No. 129,016, and depending for its operative connection 15 upon a coin which when deposited by the vendee will effect an operative connection between a manually-operated handle and the delivering mechanism of the machine. Subordinate to this general object are others which will 20 appear during the course of the succeeding description of the illustrated embodiment of the invention.

In the accompanying drawings, Figure 1 is a side elevation of the machine and its operating mechanism, one side of the casing being removed and certain parts of the structure broken away. Fig. 2 is a longitudinal sectional view through a machine equipped with my novel coin-controlled operating mechanism, a part of the casing being broken away. Fig. 3 is a rear elevation of the machine, showing the casing and certain parts of the mechanism in section. Fig. 4 is a detail view of the operating-lever and its mounting and 35 showing the swinging detent, an intermediate position of the lever being indicated in dotted lines. Fig. 5 is a detail view in perspective of one end of the two-part shaft and associated parts. Fig. 6 is a detail sectional elevation 40 showing the relation of the shaft, the coin-operated detent, and associated parts and showing in dotted lines the receiver swung down and the guard swung to its position below the discharge-opening of the coin chute 45 or race; and Fig. 7 is a sectional view through the lower end of the coin-race and through the swinging guard and coin-receiver.

Like numerals of reference are employed to designate corresponding parts throughout 50 the several views.

The vending-machine illustrated in the accompanying drawings is identical with that claimed in my concurrent application hereinbefore identified, and it will be described only in so far as is necessary to make plain the 55 manner in which it is related to the coin-controlled operating mechanism to be specifically described and claimed in this application.

Within a suitable casing 1 is mounted a machine-frame 2, constructed to provide a receptacle in its upper portion for a cigar-box 3, from which cigars are fed by a follower-plate 4 to a chute 5, located at the front end of the frame. From the chute 5 the cigars are deposited one at a time in the pocket 6 of a feed- 65 slide 7. As this slide is reciprocated the cigars are conveyed to the front end of the frame, where they are dropped upon a ledge 8. At the lower edge of this ledge, which latter is downwardly inclined, is disposed a movable wall 9, constituting part of a pivoted counterweighted holder 10, the wall 9 serving to prevent a cigar deposited upon the ledge 8 from escaping prematurely therefrom.

The holder is provided with trip-arms 11, 75 disposed in the path of an oscillating carrier 12, the side arms 13 of which are pivoted to the opposite sides of the frame 2 adjacent to their upper rear corners, as shown in Fig. 1. The oscillating carrier 12 includes a support 80 14, extending beyond the front ends of the arms 13, and upon this support is mounted a pivoted ejector 15, which upon the complete depression of the carrier is disposed in advance of and below the ledge 8 to receive a cigar 85 dropping from the latter upon the withdrawal of the wall 9 as the carrier reaches its depressed position.

The follower-plate 4 is operated through the movement of the feed-slide; but the mechanism for transmitting the necessary motion constitutes no part of the present invention and need not be described. The machine also embodies various adjunctive devices for regulating the feed of the cigars; but description 95 thereof will be omitted for a reason already stated.

It will now be seen that the operation of the machine depends upon the transmission of the necessary movement to the feed-slide and car- 100

rier, and it is with this operating mechanism that my present invention is particularly concerned.

At opposite sides of the frame, at or adjacent to the rear end thereof, are disposed suitable supporting-brackets 16 and 17, designed for the support of a two-part shaft, comprising what may be termed the "shaft" proper, 18, afforded bearings in the brackets 16 and 17 and surrounded by a sleeve 19, designed, except under certain conditions to be mentioned, to permit the independent rotation of the shaft. From this sleeve 19 extend a pair of arms 20, to which are pivotally connected, preferably by a cross-bar 21, a pair of pitmen 22 and a pair of links 23. The pitmen, disposed at opposite sides of the frame 2, are connected at their front ends to a shaft 24, connected to the feed-slide and having its ends extended through slots 25 in the frame-walls for connection with the pitmen. The links 23, similarly located beyond opposite sides of the frame, are pivotally connected at their upper ends to the arms 18. It will be seen from this character of connection that the sleeve 19 when rotated will swing the arms 20, thus imparting a reciprocatory movement to the feed-slide through the medium of the pitmen and an oscillatory movement to the carrier 12 through the medium of the links 23. These movements of the feed-slide and carrier are properly timed so that as the carrier is being elevated to transfer a cigar from a point in advance of the machine to a delivery-opening 35 in the top of the casing 1 the feed-slide will advance a cigar from the chute 5 to the ledge 8 for delivery to the carrier upon the complete recession of the latter through the reverse movement of the sleeve 19 and its arms 20.

We have now seen that the feeding and delivering mechanisms of the vending-machine are both connected to the sleeve 19 of the operating mechanism and that said sleeve is mounted loosely upon the shaft 18. I shall now proceed to describe the mechanism whereby a rocking or oscillatory motion is imparted to the shaft 18 from a suitable operating-handle and will then describe the coin-operated mechanism for connecting the sleeve 19 to said shaft in a manner to enable the vendee to operate the machine by the manipulation of the handle after a coin has been deposited.

Beyond the bracket 16 the shaft is provided with a crank-arm 26, (see Fig. 1,) to the wrist of which is connected the rear end of a draw-rod 27, located beyond one side of the machine-frame, and preferably rendered extensible by forming the rod in sections and by connecting the sections by a turnbuckle 28. The front extremity of the draw-rod 27 is pivotally connected, as indicated at 29, to an angular operating-lever 30, fulcrumed at 31 in a suitable bracket 32, secured within the casing 1, one end of the lever being extended through

the front wall of the casing and constituting an operating - handle 33 accessible to the vendee. It will be observed that by swinging the lever 30 the draw-rod is moved longitudinally to swing the crank-arm 26, and thereby effect the partial rotation of the shaft 18. This movement of the shaft is sufficient, provided the shaft and sleeve are properly connected, to move the carrier 12 from its normal position (shown in Figs. 1 and 2) to the delivery-opening in the casing. It will therefore be seen that when such connection has been effected the manipulation of the operating-handle in the manner specified will cause the transfer of a cigar to the delivery-opening, through which it will be projected by the tilting of the ejector 15, as described specifically in my copending application.

The mechanism for effecting the necessary connection between the sleeve and shaft includes a coin - operated detent 34, pivotally mounted upon a lug 35, projecting from the sleeve, and having at one end a beak 36, disposed normally within a slot 37 in the sleeve 19 and arranged when the detent is tilted to enter a notch or recess 38 in the shaft 18. It will be obvious that when the detent is tilted to move the beak into the notch 38 in the shaft the sleeve and shaft will be connected for rotary movement in unison; but normally the beak is held out of engagement with the notch by a counterweight 39, carried by one end of the detent and serving to retain the latter in its disengaged position, as shown in Fig. 3. The operation of the detent to connect the sleeve and shaft is designed to be effected by a coin deposited by the vendee.

At the extremity of an angular arm 40, constituting one end of the detent 34 and extending beyond the beak, is supported what may be termed "a coin receiver or cup" 41, normally located under the discharge-opening 42 of a coin chute or race 43, extending at a downward and rearward inclination from a coin-slot 44 in the top wall of the casing 1 to the rear end of the machine-frame at one side thereof, as indicated in Fig. 1. The lower extremity of this chute 43 is disposed horizontally, as shown in Fig. 7, so that when a coin is dropped through the opening 42 into the cup or receiver 41 it will not sustain the weight of more than a single coin in the event of a number of coins having been deposited in the chute. This chute is preferably secured to the upper end of the bracket 16, as shown in Fig. 3; but any other character of support would suffice.

To prevent a coin from being discharged from the chute when the receiver 41 is out of its receiving position, I provide a swinging guard 45, pivoted, as indicated at 46, just above the lower end of the chute and having its lower end bent at an angle, as indicated in Fig. 3, and disposed in one position of the guard to close the opening 42 of the coin-

chute. Let us now suppose that a coin is deposited in the slot 44, the detent being in the position shown in Fig. 3 and the guard being in the position indicated in Fig. 7. The coin 5 will gravitate through the chute and will drop through the opening 42 into the receiver 41. The weight of the coin being sufficient to overcome the counterweight 39 will swing the detent to cause the beak 36 thereof to pass into 10 the notch 38 of the shaft 18. An operative connection between the sleeve and shaft will thus be effected, and the vendee may operate the machine by swinging the operating-handle 33 to the dotted position indicated in Fig. 15 4. This operation of the handle will cause the shaft and sleeve to be turned in an obvious manner, and as the receiver 41 is movable with the sleeve it will be swung away from the lower end of the chute 43 to the dotted 20 position indicated in Fig. 6. In this position of the receiver the coin will gravitate therefrom, and as the vendee throws the handle back to its normal position the parts will be returned and the device will be ready for a 25 succeeding operation upon the deposit of another coin.

It will be noted that as soon as the receiver leaves its normal position upon the actuation of the machine the guard 45 will swing rearward to close the opening 42, as shown in dotted lines in Fig. 6, and if, therefore, another coin is deposited in the chute before the parts have been restored to their normal positions it will be detained and will not drop into the 30 casing until the receiver is again in position to receive it. It will appear, therefore, that some means must be provided for swinging the guard out of its obstructing position when the receiver moves back to a position below 35 the opening 42. To accomplish this end, I provide the sleeve 19 with a guard-operating finger 47, disposed to engage the angular end of the guard and to swing said guard back to the position indicated in Fig. 6 as the receiver 40 is moving back to receive the coin.

Ordinarily the structure as thus far described would be entirely operative and effective; but it sometimes happens that the irregular manipulation of the operating-lever 50 will relieve the clamping action of the side wall of the notch 38 against the beak of the detent, which is necessary to maintain the detent in engagement after the coin has dropped from the receiver. In this event the detent 55 swings to its disengaging position before the carrier and feed-slide have been fully retracted, and the machine elements are thus disconnected from the operating mechanism before the feeding and delivering mechanisms 60 have been properly restored to their initial positions. Ordinarily this would not be material, since the weight of the carrier is designed to be sufficient to cause the proper return of the parts upon the happening of this 65 contingency; but it is possible through lack

of a proper adjustment or for other reasons that the proper positions of the parts would not be completely restored without assistance from the operator, and I have therefore provided means independent of the detent for connecting the operating mechanism with the machine to facilitate the retraction of the parts, this means being ineffective to connect the parts when the feeding and delivering mechanisms are in their normal positions or to permit the operation of said mechanisms in other than a retractile direction. This separate connecting means is best shown in Fig. 5 of the drawings and includes a pin 48, extending from the shaft 18 through a cut-out portion 70 or opening 49 in the sleeve 19, the pin being disposed in the normal positions of the parts to abut against a wall or shoulder 50 defining one end of the opening in the sleeve. If now the handle 33 is operated prior to the deposit 80 of a coin in the chute, the shaft 18 will be rotated and the pin 48 will simply travel in the opening 49 in the sleeve without imparting movement to the latter. If, however, the sleeve and shaft are connected by the detent, 85 they will rotate in unison, the shoulder 50 and the pin 48 remaining in contact. If, therefore, the detent becomes disengaged from the shaft before the parts have been fully retracted, the depression of the handle 33 will 90 rotate the shaft, and the pin 48, abutting against the shoulder 50 of the sleeve, will compel the rotation of the latter to insure the retraction of the carrier and feed-slide.

The final feature of the present invention 95 resides in means for compelling the vendee to move the handle 33 to the extreme end of its stroke in one direction before he can move it in the opposite direction, the reason for this provision being to insure the delivery of a 100 cigar to the carrier before the latter can be moved to the delivery-opening.

Upon the bracket 32 is mounted a swinging detent 51, provided in its opposite edges with teeth designed to be engaged by a projection 105 52, extending laterally from the lever 30 at some distance from the fulcrum thereof. When the lever 30 is swung in the direction of the arrow in Fig. 4, the projection 52 will contact with one side edge of the detent and 110 will swing the latter. As the movement continues the projection will engage the successive teeth of the detent and will be dogged thereby until said projection passes beyond the end of the detent just as the lever 30 reaches 115 the limit of its movement. When the projection clears the detent in the manner stated, said detent will swing back to its normal position, and upon the reverse movement of the lever the projection 52 will engage the teeth 120 at the opposite side of the detent and will be dogged in a manner similar to that described until the end of the stroke is reached and the detent swings back, as described. It will therefore appear that if a vendee having received 125 130

a cigar from the machine fails to completely restore the handle to its normal position the next person desiring to purchase a cigar will find it impossible to raise the handle until he 5 has first depressed it sufficiently to insure the delivery of a cigar to the carrier, after which the machine may be operated to effect the delivery of a cigar through the discharge-opening at the top of the casing 1.

10 It is thought that from the foregoing the construction and operation of my coin-controlled operating mechanism will be clearly apparent; but while the illustrated embodiment of the invention is believed at this time 15 to be preferable I do not limit myself to the structural details defined, as, on the contrary, I reserve the right to effect such changes, modifications, and variations of the illustrated structure as may be fairly embraced within 20 the scope of the protection prayed.

What I claim is—

1. In coin-controlled operating mechanism, the combination with a shaft provided with a pin extending laterally therefrom adjacent to 25 one end and with a longitudinal recess, and a crank-arm extending from one end of the shaft and having means of attachment to suitable operating mechanism, of a sleeve incasing the shaft and provided with a cut-away portion at 30 one end for the accommodation of the pin, arms designed for connection with the mechanism to be operated, and a slot normally coinciding with the recess in the shaft, a detent mounted on the sleeve and provided with a beak disposed to pass through the slot in the sleeve 35 and into the recess in the shaft, a coin-receiver located at one extremity of the detent, and means at the other extremity of the detent for overbalancing the latter when the receiver is 40 empty.

2. In coin-controlled operating mechanism, the combination with a shaft, and a relatively movable sleeve, of means for operating one of 45 said elements, means for connecting the other of said elements to the mechanism to be operated, a coin-controlled detent for connecting the shaft and sleeve for movement in unison, a coin-receiver carried by the detent, a coin-chute disposed to deposit a coin in the receiver, 50 a guard movable to a position opposite the discharge-opening of the chute when the receiver is not in a position to receive a coin, and means movable with the receiver for moving the guard away from the discharge-opening of the chute when the receiver is moved to its receiving position.

3. In coin-controlled operating mechanism, the combination with a shaft, and a relatively movable sleeve, of means for operating one of 60 said elements, means for connecting the other of said elements to the mechanism to be operated, a coin-controlled detent for connecting the shaft and sleeve for movement in unison, a coin-receiver carried by the detent, a coin- 65 chute disposed to deposit a coin into the re-

ceiver, a guard movable to a position opposite the discharge-opening of the chute when the receiver is not in a position to receive a coin, and a finger extending laterally from the sleeve and disposed to engage the guard to 70 move the same.

4. In coin-controlled operating mechanism, the combination with a recessed shaft, and means for operating the same, of a shouldered sleeve mounted on the shaft, a detent pivoted 75 on the sleeve and disposed to engage the recess in the shaft, a coin-receiver carried by the detent, a coin-chute disposed to deposit a coin in the receiver, a swinging guard movable to a position opposite the discharge-opening 80 of the chute when the receiver is out of its receiving position, a finger extending from the sleeve to engage and operate the guard, a pin extending from the shaft and disposed to engage the shoulder of the sleeve, and means 85 for connecting the sleeve with the mechanism to be operated.

5. In coin-controlled operating mechanism, the combination with an operating-lever, a shaft connected to the mechanism to be operated, and coin-operated means controlling the operative connection between the mechanism to be operated and the operating-lever, of a swinging detent provided with teeth at its opposite edges, and a projection on the lever arranged to engage the opposite sides of the detent as the lever is moved in opposite directions and to pass beyond the end of the detent as the limit of the movement of the lever in either direction is reached. 95

6. In coin-controlled operating mechanism, the combination with a two-part shaft, and a coin-operated detent for connecting the parts of said shaft, of a crank-arm extending from one part of the shaft, a rod extending from 100 the crank-arm, an operating-lever connected to said rod, and a detent for dogging the operating-lever in each direction, to prevent its movement in one direction before its movement in the opposite direction has been completed. 105

7. In coin-controlled operating mechanism, the combination with a two-part shaft, and a coin-operated detent for connecting the parts of said shaft, of a crank-arm extending from 115 one part of the shaft, a rod extending from the crank-arm, an operating-lever connected to the rod and having a projection, and a swinging detent having its opposite edges toothed and arranged to be engaged and swung by the projection on the lever and to be released by the passage of said projection beyond the free end of the swinging detent. 120

In testimony that I claim the foregoing as my own I have hereto affixed my signature in 125 the presence of two witnesses.

DAVID JAMES.
